UNITED STATES PATENT OFFICE.

AUSTIN D. SEARLS, SR., OF SEWARD, AUSTIN D. SEARLS, JR., OF CHANNAHON,
AND DEWITT CLINTON SEARLS, OF TROY, ILLINOIS.

PULVERIZING-MACHINE.

SPECIFICATION forming part of Letters Patent No. 398,905, dated March 5, 1889.

Application filed May 28, 1888. Serial No. 275,358. (No model.)

To all whom it may concern:

Be it known that we, AUSTIN D. SEARLS, Sr., residing at Seward, in Kendall county, Illinois, AUSTIN D. SEARLS, Jr., residing at 5 Channahon, in Will county, State of Illinois, and DEWITT CLINTON SEARLS, residing at Troy, in Will County, State of Illinois, all citizens of the United States, have invented certain new and useful Improvements in Pulverizing-Machines, of which the following is a 10 specification, reference being had therein to the accompanying drawings, and the letters and figures of reference thereon, forming a part of this specification, in which—

15 Figure 1 is a side elevation of the pulverizing-machine as it would appear ready for operation. Fig. 2 is a central longitudinal vertical section of the outer case of the device, of the rotating drum and beater-head 20 therein, and a side view of a portion of its shafts and of a portion of one of the bed-sills. Fig. 3 is a vertical cross-section of the device, taken on line 1 of Figs. 1 and 2, looking in the direction of the arrow. Fig. 4 is a side 25 plan view of the rotating drum and of the rotating beater-head, taken on line 2 of Fig. 2, looking in the direction of the arrow; and Fig. 5 is an enlarged central vertical section 30 of the outer case of the rotating drum and beater-head therein and a side elevation of the boxes supporting the shafts of said drum and beater-head and of the drive-pulleys and fly-wheels on said shafts.

This invention relates to certain improvements in the pulverizing-machine for which 35 Letters Patent of the United States were granted to us, dated January 10, A. D. 1888, No. 376,112.

Referring to the accompanying drawings, 40 and the letters and figures of reference thereon, A represents a pair of parallel bed-sills, to which are securely attached the stationary parts of the machine, which bed-sills are arranged a little distance apart and connected 45 by suitable cross-beams to form a strong solid frame.

O and O' represent standard-boxes securely bolted to the sills A in such position as to be exactly in line with each other.

50 S and S' represent a pair of shafts arranged, respectively, in boxes O and O' in such man-

ner that their facing ends nearly meet and their opposite ends project a short distance from their respective outer box.

D represents a rotating drum having its inner head, D⁶, secured to a hub, D², secured on the inner end of the shaft S'. The opposite head, D', of said drum is provided with a central circular feed-opening surrounding the inner end of the shaft S, which opening is provided with an outwardly-extending flange or collar, D⁴, arranged to nearly meet the inner side of the outer case, C, inclosing said drum, as near as possible to form a close connection to prevent escape of pulverized material between them, as is shown in Fig. 2. The heads of said drum are respectively provided with annular chambers in their inner sides, near their peripheries, for the purpose of securing therein removable lining-plates a and a', for 65 preventing wear of the said heads at that place by the material under treatment. These plates are securely held in place by means of bolts or screws, and are intended to be of sufficient thickness to just fill said annular chambers 70 in which they are placed. The inner peripheral surface of said drum is provided with removable beater-plates R, secured in place by means of bolts or screws, the faces of which plates may be formed with vertical offsets and 75 inclines, as shown in Figs. 3 and 4, or may be corrugated or of any suitable form adapted to operate on the material to be pulverized. The head D⁶ of said drum, secured to hub D² on shaft S', is provided with small exit-perforations V in its part immediately surrounding its said hub and between said hub and the lining-plates a of said head, as shown in 80 Figs. 2 and 4.

D⁵ represents a rotating beater-head formed 85 of the hub II, secured on the inner end of shaft S, radial arms y, projecting from said hub, and removable beater-plates d, secured to the outer ends of said arms, as shown in Figs. 2, 3, and 4. These arms and beater- 90 plates may be connected, if desired, by means of the braces d', as shown in Fig. 4, for mutual 95 support and strength to the parts.

C is a stationary case inclosing said drum and beater-head, which case is constructed in 100 two parts, hinged together at one side and secured together at the opposite side from

said hinge by means of the latch *t*, and is secured to said bed-sills by means of its feet *Z*, securely bolted thereto. Said case closely fits the shafts *S S'*, passing through its sides to 5 prevent the material under treatment from escaping between said shafts and case.

F is a feed-supply pipe or spout extending through the side of the said case and through the central opening in head *D'* of the drum, 10 through which material to be pulverized is conducted to the chamber within said drum surrounding the beater-head *D⁵*, arranged therein.

E is an exit-pipe arranged in the side of 15 said case opposite to said feed-pipe, to which exit-pipe is applied a suction air-blower, *G*.

P P' are belt-pulleys respectively secured on shafts *S* and *S'*, to which pulleys belts may be applied in the ordinary manner to rotate 20 said shafts and their fixed parts in opposite directions.

I and *I'* are fly-wheels respectively secured to the outer ends of shafts *S S'* for governing their speed.

25 In operation the material to be pulverized is admitted through the feed-pipe *F* from a supply above, and is rapidly drawn in by means of the suction air-blower, where it comes in contact with a rapid current of air traveling with and caused by the rapid rotation of said beater-head. The said current, together with the arms and beaters of said beater-head, throws the material radially into an opposite rotating current of air, caused by the

30 opposite rotation of the drum, and against material clinging to the inner surface of said drum and the beaters attached thereto, causing rapid disintegration of the material, more from its contact with its particles than with any part of the machine, by utilizing the two oppositely-rotating currents of air by means of rotating the drum and beater-head in opposite directions, and without much wear on any part of the machine. The suction air-blower causes a cross-current of air to pass

35 through the machine, which not only assists in feeding in and disintegrating the material, but withdraws the lighter pulverized material as fast as accumulated from the drum 40 through the perforations *V* and from any part of the case, as indicated by the arrows 1 2 3 in Fig. 2. The centrifugal force of the drum and

beater-head has the tendency to throw the heavier particles of the material outward against the beaters *R* and the accumulated 55 material clinging to them, where they are ground to a fine powder, which gathers more toward the center of the drum, so it can be withdrawn through the perforations by means of the suction air-blower, as stated. The machine is intended to pulverize stone or ore, but may be used to pulverize any material to which it is adapted.

Having thus described our invention, what we claim as new, and desire to secure by Letters Patent, is as follows, to wit:

1. In the pulverizing-machine shown and described, the combination of the drum *D*, having its inner head, *D⁶*, provided with the perforations *V*, surrounding its hub and the removable lining-plates *a*, the notched beater-plates *R*, arranged on its inner peripheral surface, the head *D'*, having a central feed-opening and the removable lining-plates *a'*, the beater-head *D⁵*, consisting of the hub *H*, 75 radial arms *y*, and beaters *d*, secured to the outer ends of said arms, and the case *C*, the said beater-head *D⁵* arranged within said drum and adapted to rotate in an opposite direction therefrom, substantially as and for 80 the purpose set forth.

2. The combination, with the case *C*, consisting of two parts hinged together and having the feed-pipe *F*, and the exit-pipe *E*, arranged on the side of said case opposite to 85 said feed-pipe, shaft *S*, beater-head *D⁵*, consisting of the hub *H*, secured on the inner end of said shaft and having radial arms *y*, and beater-plates *d*, secured on the outer ends of said arms, shaft *S'*, rotatable drum *D*, consisting of hub *D²*, secured on said shaft, head *D⁶*, having the central perforations, *V*, and the removable lining-plates *a*, and head *D'*, having the central feed-opening surrounded by the outwardly-projecting flange *D⁴*, and having 90 the removable lining-plates *a'*, all arranged to operate substantially as and for the purpose set forth.
